CLAIM

The ornamental design for a pole handle for sports equipment, as shown and described.

DESCRIPTION

FIG. 1 is a front view thereof of a first design;
FIG. 2 is a left side view thereof; the right side view is a mirror image of the left side view of a first design;
FIG. 3 is a rear view thereof of a first design;
FIG. 4 is a top plan view thereof of a first design;
FIG. 5 is a bottom plan view thereof of a first design;
FIG. 6 is a perspective view from a front left side thereof of a first design;
FIG. 7 is a perspective view from a rear left side thereof of a first design;
FIG. 8 is a perspective view from a front left side thereof of a first design;
FIG. 9 is a perspective view from a rear left side thereof of a first design;
FIG. 10 is a front view thereof of a second design;
FIG. 11 is a left side view thereof; the right side view is a mirror image of the left side view of a second design;
FIG. 12 is a rear view thereof of a second design;
FIG. 13 is a top plan view thereof of a second design;
FIG. 14 is a bottom plan view thereof of a second design;
FIG. 15 is a perspective view from a front left side thereof of a second design; and,
FIG. 16 is a perspective view from a rear left side thereof of a second design.

The broken lines are for the purpose of showing environmental structure only and form no part of the claimed design.
